UNITED STATES PATENT OFFICE.

PAUL KRAUSE, OF BABYLON, NEW YORK.

INTERNAL-COMBUSTION TURBINE.

No. 918,679.

Specification of Letters Patent. Patented April 20, 1909.

Application filed October 10, 1907. Serial No. 396,758.

To all whom it may concern:

Be it known that I, PAUL KRAUSE, a citizen of the United States, and a resident of Babylon, in the county of Suffolk and State 5 of New York, have invented a new and Improved Internal - Combustion Turbine, of which the following is a full, clear, and exact description.

This invention relates to certain improvements in turbines, and more particularly to special construction whereby successive charges of an explosive mixture are ignited and the resulting gases under high pressure are delivered into engagement with the vanes 15 or blades of the turbine.

The specific construction illustrated involves certain improvements over the previous construction illustrated in my Patent Number 880,458, granted February 25, 1908, 20 such improvements relating more particularly to the valve, means for controlling the same, and the means for compressing the explosive charge and delivering it to the turbine proper.

Reference is to be had to the accompanying drawings, forming a part of this specification, in which similar characters of reference indicate corresponding parts in all the figures, and in which—

Figure 1 is an elevation of an engine constructed in accordance with my invention; Figs. 2, 3 and 4 are successively portions of a longitudinal section through the engine shown in Fig. 1; Fig. 5 is an enlarged section 35 similar to the left-hand portion of Fig. 2, but showing the parts in the position they occupy at the beginning of the suction stroke of the compressor; and Fig. 6 is a view similar to Fig. 5, but showing the parts in the position 40 they occupy at the beginning of the compression stroke.

In the improved turbine illustrated in the accompanying drawings I employ an inner casing 10 and an outer casing 11 spaced apart 45 to form an annular chamber therebetween, and each of the casings carries a plurality of rows of blades or vanes 12 and 13 extending into this annular chamber and adapted to be engaged by the high pressure gases as they 50 move longitudinally of the casings. Both of the casings are preferably so mounted as to rotate, their rotation being in opposite directions. As illustrated, the outer casing 11 is provided with a ball bearing race-ring 14, at 55 one end thereof, spaced from a stationary

race-ring 15 by a plurality of rows of balls so disposed as to resist end thrust on the casing in either direction, as well as to support the end of the casing. At the opposite end of the casing it is also mounted in ball bearings 60 16, which need not necessarily be constructed to resist end thrust. The inner end of the inner casing 10 terminates adjacent the inlet end of the outer casing 11 and is held concentric therewith by suitable ball bearings. As 65 shown the inlet end of the casing 11 carries a spider having a central hub 17 extending into the end of the inner casing and operating to support the same, and also preventing the admission of the high pressure gases to the 70 interior of the inner casing. The inner casing extends beyond the outer casing at the outlet end of the latter and carries a ball bearing race-ring 18, spaced from suitable stationary race-rings 19 by anti-friction balls 75 to resist end thrust upon the inner casing and to support the end thereof.

The outer race-ring of both sets of ball bearings of the outer casing and of the bearing at the outer end of the inner casing are 80 preferably mounted in a stationary skeleton frame 20 inclosing the casing. The two casings are connected together at their outer gearing, whereby they are caused to rotate in opposite directions and at the desired 85 speed in respect to each other. As shown, the outer casing carries a gear 21 intermeshing with a gear 22 on a short shaft 23, which shaft also carries a gear 24 intermeshing with a gear 25, in turn meshing with a gear 26 carried by the inner casing. The shaft 23 is thus connected by chains of gears to both casings, the number of gears being different, whereby the opposite direction of rotation is brought about. Adjacent this gearing is an 90 outlet for the high pressure gases, said outlet preferably including a radial flange 27 carried by the inner casing to prevent the escape of the gases against one chain of gears, and a second radial flange 28 carried by the 100 outer casing to prevent the contact of the gases with the other chain of gears and the ball bearings 16. Both flanges preferably include in their construction asbestos or other suitable non-heat conducting material. 105 If desired, one of the flanges may be provided with an annular perforated plate 29, extending to a point adjacent the other flange, or, if desired, this annular plate may be from both of the flanges and be supported

by the skeleton frame 20. The outer end of the inner casing 10 extends beyond the ball bearing support thereof and is keyed to a large drum 30 operating as a fly wheel and 5 also constituting means for operating the piston of the compressor and operating the valve controlling the flow of gas from the compressor to the blades of the turbine.

The compression cylinder 31 is preferably 10 rigidly connected to the inlet end of the outer casing 11, and communication between the two is controlled by a longitudinally-movable valve 32. This valve is carried by a valve stem 33 extending through 15 the hub 17 and through the inner casing, said hub being provided with a recess adapted for the reception of the valve when the latter is opened to the limiting position. With the valve open the gas may flow directly from 20 the interior of the compression cylinder to the annular space between the casings, as will be noted from Fig. 3. The valve-operating rod 33 extends the full length of the casing to the interior of the drum 30, and is 25 there supported by a suitable collar 34 connected to the end of the inner casing. For opening the valve I rely upon the excessive pressure within the compression cylinder at the time of the ignition of the gas, but provide special mechanism for normally holding 30 the valve closed.

As shown, a branch 35 of the skeleton frame extends past the drum 30, and is bent around to extend into the interior thereof 35 from the outer side. This branch supports a radially-disposed lever 36, one end of which carries a roller 37 engaging in a groove 38 in the inner surface of the drum and the other end of which extends to a point in 40 alinement with the valve rod 33. The lever does not engage directly with the end of the valve rod but is connected thereto by resilient connections, whereby the valve 32 may open at the instant of the explosion irrespective of the lever 36 in case of premature 45 explosion. These resilient connections preferably include a spring arm 39, one end of which is rigidly connected to the lever and the other end of which presses against the 50 end of the valve rod. To reinforce the spring arm I provide a spring plunger 40 in direct alinement with the end of the valve rod and normally held against the side of the spring lever by a coil spring 41. The combined action of the spring arm and the 55 spring-pressed plunger holds the valve 32 firmly against its seat when the lever is in the position shown in Fig. 4. At the proper time in the rotation of the drum, an offset in 60 the groove 38 removes the lever and its resilient connections from engagement with the valve rod, and the valve may freely open. The explosion in the compression cylinder and the movement of the lever 36 are normally simultaneous, the resilient connec- 65

tions merely serving to permit an opening of the valve in case of an explosion before the lever 36 recedes.

As previously stated, the compression cylinder 31 is rigidly connected to the outer casing in alinement therewith and is rotated thereby. Within the compression cylinder, which also serves as the combustion chamber, there is provided a piston 42 also in alinement with the turbine casings and movable longitudinally of the compression chamber. The piston is rigidly connected to a piston rod 43, which may or may not rotate with the cylinder 31, as desired. As shown, the piston rod is so connected that it and the piston may freely rotate. The piston is operated from the drum 30 by means of two operating rods 44, extending longitudinally of the engine and each having one end thereof flattened to slide in a corresponding guide 45, 85 and having a roller for engagement in a cam groove in the surface of the drum. The two grooves may be so disposed as not to cross each other, or one roller 46 may be made wide and shallow, while the other roller 47 may be made narrow and deep, so that neither roller can enter the groove of the other roller should the two grooves cross. The opposite end of each rod 44 is connected to a cross head 48 in engagement with the piston rod 43 and, preferably separated therefrom by two rows of anti-friction balls disposed upon opposite sides of a flange 49 carried by the piston rod. As the drum 30 rotates, the cam grooves thereof engage with the rollers 46 and 47 to move the two rods 44 back and forth to operate the piston within the compression chamber, but permitting the piston and piston rod to freely rotate within the cross head 4. 105

The piston rod is hollow and serves as a means for supplying the explosive mixture to the compression chamber, the inner end of the piston rod being provided with a valve 50 controlling the connection between the interior of the piston rod and the interior of the cylinder. Adjacent the outer end of the piston rod it extends through two packing boxes at the ends of a sleeve 51. The sleeve and packing boxes are preferably supported by transverse members 52, constituting a part of the skeleton frame 20 and serving as means for supporting the hollow piston rod. A suitable inlet pipe 52 connects the sleeve 51 to any suitable source of explosive mixture, and the portion of the piston rod within the sleeve is provided with perforations whereby the explosive mixture may gain access to the interior of the piston rod. Within the piston rod and beyond the perforations, there is provided a partition 54 preventing the explosive mixture from passing out at the rear end of the rod. 115 120 125

The valve 50 is connected to a valve rod 55 extending longitudinally of the hollow piston 130

rod and terminating adjacent the outer end of the latter. The valve rod is supported in any suitable manner and extends through the partition 54 above referred to. For normally holding the valve closed there is provided a coil spring 56 within the tube and in engagement with said partition and a shoulder or collar 57 on the valve rod. The outer end of the piston rod carries means for engaging with the valve rod 55 to open the valve 50 and hold it open during the outward movement of the piston, and to release the valve rod and permit the valve to close during the return movement of the piston. This mechanism, illustrated on an enlarged scale in Figs. 5 and 6, involves a lever 58 pivoted in the wall of the piston rod adjacent its outer end and extending diametrically across the piston rod and also extending outward a short distance therefrom. The inner end of the lever is normally in engagement with the end of the valve rod, and the outer end of the lever is adapted to engage with a portion of one of the transverse supports 52 of the skeleton frame when the piston is moved inward to nearly its limiting position. The transverse support 52 is illustrated as being provided with an annular flange 59, so disposed that with the piston in its innermost position, the inner end of the lever 58 will be forced still farther and open the valve inwardly into the cylinder.

Adjacent the inner end of the lever 58, there is provided a catch 60 normally pressed inwardly into the path of said lever by the action of a suitable spring. The inner end of the catch is beveled, so that when the lever is moved to the position indicated in Fig. 5, it cannot return, and the valve 50 is held open against the action of the spring 56. The piston then moves outwardly with the valve open and draws in a charge through the inlet pipe 53 and hollow piston rod. When the piston reaches the outer end of its stroke, mechanism engages with the catch 60 to withdraw the same and release the lever 58, whereupon the spring 56 closes the valve. This releasing mechanism preferably includes a transverse member 61, also constituting a portion of the skeleton frame and having an annular flange 62 concentric with the piston rod. Adjacent the outer end of the spring-pressed catch 60 is a pin 63 normally held in its outermost position by a spring 64 and having a cam surface in engagement with a portion of the catch to withdraw the same. With the piston rod in its outermost position, as shown in Fig. 6, the end of the pin 63 engages with the annular flange 62 and forces the pin inwardly against the action of the spring 64. This withdraws the catch 60 to liberate the lever 58, and the valve 50 closes.

The piston in its movement travels the full length of the cylinder, and the inward stroke serves the double purpose of com-

pressing the explosive charge and scavenging the exhaust gas. The explosion takes place in the compression cylinder when the piston has traveled a predetermined portion of its stroke, and the high pressure gases escape past the valve 32 into engagement with the turbine blades. The piston 42 completed its stroke to remove all of these gases from the cylinder. The explosion is timed to occur at the instant the valve 32 is opened, and this explosion may be brought about by any suitable igniter, as, for instance, a spark plug 65, the circuit being closed by the engagement of a brush on the spark plug and a corresponding contact 66 supported by the frame.

While the piston is making its compression stroke and is being moved forward by the collar 49, the explosion occurs. At this time I bring into operation auxiliary mechanism for resisting end thrust and preventing the return movement of the piston. This mechanism preferably includes a slide 67 transversely movable in a transverse member 68 rigid with the skeleton frame and adapted to be moved into engagement with the rear end of the piston rod at the instant of explosion. The slide 67 is firmly supported against movement in the direction of the movement of the piston rod, and carries a ball 69 or other anti-friction means for engaging with the end of the piston rod. The outer end of the slide carries a pin 70 extending into the cam slot of a sliding plate 71, which plate is intermittently moved longitudinally to draw in or shove out the slide 67. As illustrated, the plate is operated by a rod 72 extending longitudinally of the engine and having a roller engaging in a cam groove 73 of an auxiliary drum 74 carried by the main drum 30. The slide 67 normally occupies a position out of the path of the piston rod, as illustrated in Figs. 5 and 6; but while the piston rod is moving inwardly on the compression stroke, the slide 67 is moved downwardly to the position illustrated in Fig. 2, reaching said position at the instant the piston rod has passed and at the instant the explosion occurs. While the piston is completing its stroke, the slide 67 is moved out of the path and permits the free movement of the piston rod. Thus, the shock of the piston at the time of the explosion, which would normally be borne by the flange 49, is almost entirely borne by the much stronger and better supported slide 67.

Any suitable means may be provided for cooling the rotating compression cylinder and the rotating turbine casing. As illustrated, I have provided the compression cylinder with a plurality of radially-disposed fan blades 75 operating to blow air longitudinally of both the cylinder and the casing, while the two are rotating. A separate set of these fan blades may be provided, if desired, for the turbine casing.

Having thus described my invention, I claim as new and desire to secure by Letters Patent:

1. In combination, a rotatable turbine casing having a plurality of blades or vanes, a compression cylinder attached thereto and in alinement and rotatable therewith, a valve for controlling communication between said cylinder and said casing, a piston movable longitudinally of said cylinder and adapted to compress an explosive charge therein, and means for igniting said charge.
2. In combination, a rotatable turbine casing, a combustion chamber in alinement therewith and rigidly connected thereto, means for igniting an explosive charge within said chamber, and radially-disposed fan blades carried by said chamber and adapted to create a circulation of air in engagement 20 with the outer surface thereof.
3. In combination, a rotatable turbine casing, a rotatable combustion chamber in alinement therewith and rigidly connected thereto, a valve for controlling the communication between the chamber and the casing, means for delivering an explosive charge to said chamber, and a plurality of radially-disposed fan blades adapted to create a circulation of air over said chamber and said casing.
4. In combination, means for compressing an explosive charge, including a compression chamber, a piston movable therein, means for operating said piston, means for igniting the charge within said chamber and while the piston is intermediate the ends of its stroke, and means separate from said piston-moving means and operable to resist the return movement of the piston at the time of the explosion, said cylinder being scavenged by 40 the completing of the piston stroke after the explosion.
5. In combination, means for compressing an explosive charge, including a compression chamber and a movable piston, means for igniting the charge within said chamber and while the piston is intermediate the ends of its stroke, a piston rod connected to said piston, and means adapted to intermittently engage with said piston rod and resist the 50 return movement of the piston at the time of the explosion.
6. In combination, means for compressing an explosive charge, including a compression chamber and a movable piston, means for igniting the charge within said chamber and while the piston is intermediate the ends of its stroke, a piston rod connected to said piston, and means adapted to intermittently engage with said piston rod and resist the 60 return movement of the piston at the time of the explosion, said means including a member movable transversely of the path of the piston.
7. In combination, means for compressing 65 an explosive charge, including a compression

chamber, a piston movable therein, a hollow piston rod connected to said piston and adapted to communicate with said compression chamber, a valve for controlling the passage through said piston rod, means for locking said valve in its open position during each alternate stroke of the piston and locking it in its closed position during the remaining strokes, and means for igniting the explosive charge within said chamber.

8. In combination, means for compressing an explosive charge, including a compression chamber and a piston movable therein, means within said chamber for igniting the charge, rotatable means operated by the products of combustion, means connecting said rotatable means to said piston for operating the latter, and auxiliary means intermittently operating to resist the return movement of the piston at the time of the 85 explosion and intermediate the ends of the piston stroke.

9. In combination, two concentric casings, spaced apart to form an annular chamber therebetween, vanes or blades carried by said casings and extending into said annular space, a combustion chamber communicating with said space, a valve for controlling the escape of gas from said chamber to said annular space, a valve rod connected to said valve and extending through said inner casing, means carried by said inner casing adjacent its outer end and presenting a cam surface, and means engaging with said surface and with said valve rod for operating said 100 valve.

10. In combination, two concentric casings spaced apart to form an annular chamber therebetween, vanes or blades carried by said casing and extending into said annular space, a combustion chamber communicating with said space, a valve for controlling the escape of gas from said chamber to said annular space, a valve rod connected to said valve and extending through said inner casing, a drum carried by said inner casing adjacent its outer end and having a cam groove, and means engaging with said surface and with said valve rod for operating said valve.

11. In combination, two concentric casings spaced apart to form an annular chamber therebetween, vanes or blades carried by said casing and extending into said annular space, a combustion chamber communicating with said space, a valve for controlling the escape of gas from said chamber to said annular space, a valve rod connected to said valve and extending through said inner casing, a drum carried by said inner casing adjacent its outer end and having a cam groove, 125 and a pivoted lever having one end thereof operated by said cam groove and having the opposite end thereof operatively connected to said valve rod.

12. In combination, two concentric cas- 130

- ings spaced apart to form an annular chamber therebetween, vanes or blades carried by said casing and extending into said annular space, a combustion chamber communicating with said space, a valve for controlling the escape of gas from said chamber to said annular space, a valve rod connected to said valve and extending through said inner casing, a drum carried by said inner casing adjacent its outer end and having a cam groove, a pivoted lever having one end thereof in engagement with said cam groove, and resilient connections between the opposite end of said lever and said valve rod.
- 10 13. In combination, an outer casing, an inner casing forming therewith an annular space, vanes or blades carried by said casings and extending into said annular space, a combustion chamber in alinement with said casings and delivering to said annular space, 20 a valve for controlling the flow of gases from said chamber to said space, a valve operated rod extending through the inner casing, a drum connected to the end of said inner casing and presenting a plurality of cam grooves, 25 means in engagement with one of said grooves for operating said valve rod, and means having operative engagement in the other of said grooves for compressing the explosive charge within said chamber.
- 15 In testimony whereof I have signed my name to this specification in the presence of two subscribing witnesses.
13. In combination, an outer casing, an inner casing forming therewith an annular space, vanes or blades carried by said casings and extending into said annular space, a combustion chamber in alinement with said

Witnesses:
